Patented Nov. 4, 1969

215,916

DISPLAY STAND FOR ALCOHOLIC BEVERAGES OR THE LIKE

Louis Forman, Jenkintown, Pa. (2218 Girard Trust Building, Broad and South Penn Square, Philadelphia, Pa. 19102)

Filed June 27, 1968, Ser. No. 12,522

Term of patent 3½ years

Int. Cl. D20—99

U.S. Cl. D96—12

FIG. 1.

FIG. 2.

FIG. 5.

FIG. 3.

FIG. 4.

I claim:

The ornamental design for a display stand for alcoholic beverages or the like, as shown and described.
